MATERIAL HANDLING TRUCK

Daniel C. Jones, Port Washington, Wis., assignor to Koehring Company, Milwaukee, Wis.

Application April 3, 1958, Serial No. 50,322

Term of patent 14 years

(Cl. D14—3)

The essential features of my design reside in those portions shown in full lines.

I claim:

The ornamental design for a material handling truck, substantially as shown and described.
